UNITED STATES PATENT OFFICE

GWILYM DAVID JONES, OF OAK CREEK, COLORADO, ASSIGNOR OF ONE-HALF TO
BENJAMIN W. SNODGRASS, OF DENVER, COLORADO

POWER TRANSFERRING DEVICE

Application filed March 25, 1929. Serial No. 349,581.

The present invention relates to power transferring or transmitting means or the like.

Among the objects of the invention is to provide a novel mechanism for transferring and directing or imparting power and motion through suitable connecting elements, such as cables, or the like to means to be operated, such as oscillating mining conveyors or the like, the power being derived from a central source of power.

The invention is particularly adapted for use with mining conveyors, such as those of the oscillating shovel, pan or flight type and arranged with a series in a main passage and auxiliary or branch or contributary series in branch or side passages or mine rooms, all so related to deliver mined material to the main series which in turn delivers the material to cars or the like, at some suitable delivery part of the mine, such as at the mouth thereof. To have independent and separate operating means at different points in the mine, for operating each series of flights, would be inconvenient, impractical and costly.

The present invention comprehends the avoidance of such difficulties by using a single source of power, and connecting the series of flights by suitable power transmitting elements, such as cables or the like to such flights. At the junction of a series with another, means being provided for transferring or diverting a part of the power being transmitted to a series, to the other series which may branch off or radiate from the junction in any of a number of angular directions.

In a specific embodiment illustrative of the invention such a device comprises a circular bell crank rotatably carried by an upright member, as a jack, and having a rim upon which are clamping means adapted to engage the rim at any point, the clamping means being adapted for engaging power transmitting cables. The clamps are preferably pivotally connected to the device to compensate and accommodate for the difference of movements of the arms which move angularly, and the cables which move substantially linearly.

The cable for each series of flights may be looped such that the two ends of the cable are connected to a rocking member of the power source and the loop or bend is at the far end of the main passage and passes over a pulley or the like, such that the two sides or sections of the cable are parallel and extend along the main passage and the main series of flights. The rocking member of the power source will pull on one of these sections and let up on the other and vice versa, so that there is a to-and-fro movement of the cable along the length thereof. One of these cables may be connected at different points to each flight of the series so that the pull of the cable will be independently effective on each flight at the connection thereof.

Where the cable sections pass by side, or branch passage or rooms, the crank means of the present invention is located, and the clamps thereof connected to the cable sections, at such locus. Thus, as the cable sections are moved linearly in opposite directions and by reason of their being adjustably connected oppositely around the rim of the crank device, the latter is simultaneously swung or angularly moved to and fro with the to-and-fro movements of the cable sections connected thereto.

A similar cable arrangement is used for the lateral or branch series of flights, with the two sides or sections of the cable connected to clamping devices adjustably connected oppositely on the rim of the crank device.

Whenever conveyors or like mechanism of the type described is used, it is often desired to extend the same in a plurality of lateral directions and to drive the entire mechanism from a central source of power. The present invention relates to suitable mechanism for directing movement in a power transmitting element from a main conveyor section to similar conveyors extending laterally thereto and driven by a like power transmitting element for imparting a movement to the individual pans or flights thereon in such a manner as to progressively cause the material to move toward the main conveyor.

In a specific embodiment selected to ill-

lustrate the invention, a circular bell crank is rotatably carried by a shaft at the junction of the main conveyor and a similar conveyor extending laterally at any angle thereto. The cable of the main conveyor is connected at a given point of the rim of the crank while a similar cable of the laterally extending conveyor is attached to another point on that rim. As the oscillating movements are imparted to the main cable from the central power mechanism, they are transmitted about the bell crank to the cable connected to the pans or flights of the laterally extending conveyor. The latter cable imparts similar oscillating movements to the latter conveyor.

A further object of the invention is to provide a novel connecting means for the cables. In the specific embodiment selected to disclose the invention, a clamp support is provided in which a clamp is pivotally mounted, and which has a bifurcated body portion engaging the rim of the crank member and adjustably positioned about such rim. A pin, bolt or the like passing through the support and engaging the rim of the movable member holds the support substantially in rigid position.

A further object of the invention is to provide a novel device to which a power transmitting element may be attached at any point thereon and in any angular relation to a similar transmitting element communicating with a central power mechanism.

Another object of the invention is to provide a novel device which may be readily and easily connected to a shaft or the like which is stably positioned and which cannot be easily moved under the operating stresses but which can be readily set in place and taken down when desired. The invention comprehends a device comprising a two part casting, each part of which may be positioned about a shaft, such as a jack in a mine or some other shoring means. These parts may be bolted or connected together by any other suitable means.

The invention further comprehends the construction of a novel clamping device comprising cable gripping parts, one of such parts being provided with pivotal means for pivotally supporting the device. The gripping parts of the clamping device are provided with reversely curved surfaces and are lined or covered with soft material to prevent injury to the cable or similar power transmitting element engaged thereby. The curved surfaces of the clamp cause the element to bend and effectively grip the same.

Other objects, features, capabilities and advantages are comprehended by the invention as will later appear, and as are inherently possessed thereby.

Referring to the drawings:

Fig. 1 is a plan view of a device constructed in accordance with the invention, and

Fig. 2 is a cross sectional view taken in the plane represented by line 2-2 in Fig. 1 of the drawings.

Referring now more in detail to the drawings, the embodiment selected to disclose the invention, comprises a two part circular bell crank 1, fulcrumed or pivoted to a shaft 2 of a jack or other shoring means placed at the junction point of a main shaft and a laterally extending or branch shaft in a mine. An endless cable 3 passes about a sheave pulley or the like at the end of the shaft and is connected to a mechanism at a central source of power, which mechanism produces a reciprocal jerking movement in the cable, which in turn is transmitted to a series of pans or flights of the conveyor positioned in the main shaft, the cable being connected to such flights.

The two-part circular bell crank comprises two castings 4 of similar construction, and each is provided with a hub part 5 positioned about the shaft 2 and pivotally mounted thereon. Spokes 6 extend radially outwardly from the hub and are connected to a circular rim 7. Lugs 8 are provided which extend inwardly from the ends of the semi-circumferential portions of the castings 4. In an assembled position, bolts 9 passing through the lugs 8 and bolts 10 passing through the hub 5, connect and hold the casting parts 4 in a pivotal position about the shaft 2. Spaced bolt holes 11 are provided about the rim of the bell crank. Spaced notches 12 are also provided about the periphery of the rim 7, and intermediate or in staggered relation with the bolt holes 11, the utility of which will later more fully appear.

A clamp support 12^a is provided with a bifurcated portion 13, which slidably engages the rim 7 of the bell crank 1. The bifurcated portion 13 is provided with bolt holes 14, similarly spaced as the bolt holes 11 on the rim 7 of the crank bell 1. This support is adjustable around the rim 7 and is held in any of its selected positions by bolts 15 passing through holes 14 of the bifurcated portion 13 and a pair of holes 11 on the rim 7.

A lock pin 16 passing through another hole in the bifurcated portion 13, engages one of the notches 12 on the periphery of the rim 7 to lock and rigidly hold the support 12^a to the crank bell. The outwardly extending portion of the support 12^a is bifurcated as at 17 and carries a clamp 18. A headed pin 19 passes through the bifurcated end portion 17 and through the clamp 18 and is held in position by a washer 19^a and cotter pin 20, pin 19 pivotally positions the clamp 18 in the bifurcated end portion 17.

The cable or power transmitting element 3 is gripped by the clamp 18 and the jerking movements occurring in the cable 3 are trans-

mitted through the clamping mechanism to produce an oscillating or alternate rotary movement in the bell crank. A similar clamping device as the one described, is provided and may be positioned diametrically opposite thereto on the rim 7, to engage and grip the other side or section of the endless power transmitting element or cable 3. A clamp mechanism 21 of similar construction 5 to the clamp mechanism previously described, is connected to the rim 7 of the bell crank at any given point for connection with a cable 22. This cable is connected to the pans or flights of a flexible conveyor which 10 extends laterally or branches off at any angle to the main conveyor. A similar clamping mechanism may be provided and positioned diametrically opposite to the clamping mechanism 21, for engaging and gripping the 15 other side or section of the endless cable or power transmitting element 22.

It will be seen that the jerking movements occurring in the power transmitting element 3 will be transferred through the bell crank 25 1, to the power transmitting element 22 to produce like jerking movements therein which are in turn transferred to the pans or flights of the laterally extending conveyor. The adjustable feature of these clamping devices or mechanisms permit the use of such a 30 device as herein described at a junction point where the conveyor branches or extends laterally to the main conveyor at any angle.

While I have herein described and upon 35 the drawings shown an illustrative embodiment of the invention, it is to be understood that the invention is not limited thereto, but comprehends other constructions, features, details and arrangements of parts without 40 departing from the spirit thereof.

Having thus disclosed the invention, I claim:

1. A device for transferring power in 45 different directions, comprising a movable member, said member being provided with notches spaced therealong, a clamp support slidably mounted on said member, means connecting said support to said member, means through said support and engaging a 50 notch on said member for rigidly holding said support relative to said member, and a clamp carried by said support for gripping a power transmitting element.

2. A device for transferring power in 55 different directions, comprising a movable member, said member being provided with notches spaced therealong, a clamp support slidably mounted on said member, means connecting said support to said member, 60 means through said support and engaging a notch on said member for rigidly holding said support relative to said member, and a clamp pivotally carried by said support for gripping a power transmitting element.

3. A device for transferring oscillating

movement in different directions, comprising a movable member, a clamp support adjustably engaging said member, means for connecting said support to said member in any of its adjustable positions, means mounted in 70 said support and adapted to engage the periphery of said member for rigidly holding said support relative to said member, and a clamp carried by said support for gripping a power transmitting element. 75

4. A device for transferring power in different directions, comprising a movable member, a clamp support adjustably engaging said member, said support provided with a bifurcated arm, means for connecting said support to said member in any of its adjustable positions, a pin through said support and engaging said member for rigidly holding said support relative to said member, a clamp pivotally mounted in said bifurcated arm for gripping a power transmitting element. 80 85

5. A device for transferring oscillating movement in different directions, comprising a movable annular member, said member 90 having notches spaced around its periphery, a clamp support adjustably engaging said member, means for connecting said support to said member, means for connecting said support to said member in any of its adjustable positions, a pin through said support and engaging any selected notch for rigidly holding said support relative to said member, and a clamp carried by said support for gripping a power transmitting element. 100

6. A device for transferring oscillating movement in different directions, comprising a movable annular member, said member having notches spaced around its periphery, a clamp support adjustably engaging said 105 member, means for connecting said support to said member, means for connecting said support to said member in any of its adjustable positions, a pin through said support and engaging any selected notch for rigidly holding said support relative to said member, and a clamp pivotally carried by said support for gripping a power transmitting element. 110

In witness whereof, I hereunto subscribe my name to this specification.

GWILYM DAVID JONES.
